UNITED STATES PATENT OFFICE.

WILLIAM TAYLOR, OF LEICESTER, ENGLAND.

METHOD OF GRINDING GLASS.

1,401,830.

Specification of Letters Patent. Patented Dec. 27, 1921.

Original application filed October 28, 1916, Serial No. 128,235. Divided and this application filed October 28, 1920. Serial No. 420,076.

To all whom it may concern:

Be it known that I, WILLIAM TAYLOR, a citizen of Great Britain, residing at Leicester, in the county of Leicestershire, England, have invented certain new and useful Improvements in Methods of Grinding Glass, fully described and represented in the following specification and the accompanying drawing, forming a part of the same.

10 This invention relates to a method of grinding glass and the like. This application is a division of my co-pending application, Serial No. 128,235, filed October 28, 1916, and is directed particularly to a 15 method for grinding a spherical surface. An object of the invention is to provide for rapidly forming a spherical surface upon a glass blank. The method is particularly adapted to the grinding of lenses which are 20 to have a deep convex curve.

The accompanying drawing illustrates diagrammatically the carrying out of the method. As shown in the drawing, the grinding is done by a cup-shaped wheel 3 25 mounted for rotation about an axis *a*—*b*. The glass disk 1 to be ground is carried by a spindle 2. The axes of the spindle 2 and the grinding wheel 3 are mounted so as to lie in the same plane. The axis of the 30 work spindle 2 is so mounted that it may be swung about an axis *C* intersecting the spindle axis at a point which is the center of the spherical surface to be formed, and preferably at right angles to the common plane 35 of these axes.

In carrying out the method of grinding, the work spindle is swung slowly to carry the work past the rapidly moving grinding edge of the wheel, preferably so that the 40 grinder attacks first the periphery of the disk and grinds inwardly toward the center. Usually the work spindle is rotated in a direction to cause the work at the place of contact with the grinding wheel to move in the 45 opposite direction to the movement of the grinding wheel at this point. The rotation of the work is desirably at a comparatively low speed, for example, about 100 revolutions per minute for grinding glass disks one 50 inch in diameter.

The grinding edge of the cup-shaped grinding wheel forms in the disk a circular step concentric to the axis of rotation of the spindle 2, as illustrated in the drawing. 55 This step is ground away inwardly while the

depth of the step is progressively decreased, as indicated by the dotted line in the drawing. Most desirably, the annular edge of the cylindrical grinding wheel is shaped back from the active outer side so as to clear 60 the ground surface. When the grinding wheel has its active outer side cylindrical and arranged as shown in the drawing, the side of the step formed in the glass is substantially perpendicular to the finished or 65 ground surface of the lens or to the shifting tangent to said surface, throughout the operation, but it is perpendicular to the original flat surface of the disk only at the end of the operation at the center of the lens 70 where the depth of the step is relatively small. In the early stages of the operation, the original surface of the disk forms, as seen in the drawing, an acute angle with the side of the step, and the consequent 75 fragility of the side of the step here facilitates the removal of the glass and enables the wheel to attack successfully a deeper step than it otherwise could.

In the operation described the grinding 80 is done upon the side of the circular step, the wheel contacting with the surface formed at the base of the step only. By the method described a deep spherically curved surface 85 is ground on the work by a single cut even when the blank upon which the operation takes place has at the beginning of the operation a flat surface or other surface not conforming to the desired spherical face. The method thus affords an extremely rapid 90 and efficient means for grinding a spherical surface upon glass blanks.

I wish it clearly understood that my invention is by no means limited to the specific procedure described in connection with the 95 accompanying drawing as illustrative of the invention.

What is claimed is:

1. The method of grinding a convex spherically curved surface upon a flat disk of 100 glass, which comprises rotating the disk upon an axis passing through the surface to be ground, forming in the surface to be ground a circular step having its center on the axis of rotation of the disk, grinding back said step to said axis by bringing successive portions of the side of the step into contact with a grinding surface moving along the portion of the side of the step with which it is in contact, and decreasing the 105 110 portion of the side of the step which is in contact with the grinding surface.

depth of the step as it is ground inwardly while varying the angle of the side of said step to the original surface of the disk so that it is acute at the beginning of the operation and substantially a right angle at the end of the operation.

2. The method of grinding a desired surface on a glass blank having a surface not conforming to the desired surface to be 10 formed, which comprises rotating the glass blank upon an axis passing through said surface, forming in said surface a circular step having its center on the axis of rotation of the blank, and grinding back said step 15 continuously from the periphery to the cen-

ter of the blank by bringing successive portions of the edge of the step into contact with a grinding surface moving along the portion of the side of the step with which it is in contact, while so varying the depth of the 20 step that successive positions of the base of the step lie upon the desired surface.

In testimony whereof I have hereunto set my hand in the presence of two subscribing witnesses.

WILLIAM TAYLOR.
